US00D760696S

(12) **United States Design Patent**
Espinosa et al.

(10) **Patent No.:** US D760,696 S
(45) **Date of Patent:** ** Jul. 5, 2016

(54) **LOUDSPEAKER**

(71) Applicant: **Meyer Sound Laboratories, Incorporated**, Berkeley, CA (US)

(72) Inventors: **Pablo Espinosa**, Pleasanton, CA (US); **Michael Schneider**, Emeryville, CA (US); **Paul Bunning**, Berkeley, CA (US); **Jon M. Arneson**, Napa, CA (US); **Katrin M. Rawks**, El Cerrito, CA (US)

(73) Assignee: **Meyer Sound Laboratories, Incorporated**, Berkeley, CA (US)

(**) Term: **15 Years**

(21) Appl. No.: **29/538,339**

(22) Filed: **Sep. 2, 2015**

(57) **CLAIM**

The ornamental design for a loudspeaker, as shown and described.

DESCRIPTION

FIG. 1 is a top front perspective view of a loudspeaker showing our new design;

FIG. 2 is a front elevational view thereof;

FIG. 3 is a right side elevational view thereof, the left side being a mirror image; and

FIG. 4 is a top plan view thereof, the bottom being a mirror image; and,

FIG. 5 is a rear elevational view thereof.

The broken lines shown in FIGS. 1-5 extending behind the front bezel of the loudspeaker represent a loudspeaker cabinet. In FIGS. 1 and 2, there is additionally a broken line representation of a horn and compression driver at the base of the horn shown in the front of the loudspeaker forms. In FIG. 3 there is a further the broken line representation of a small visible portion of the horn seen in broken lines in FIGS. 1 and 2. In FIG. 1 there is a broken line representation of an inside corner edge of the bottom port of the loudspeaker, and in FIG. 2 the broken line rectangle in the bottom port of the loudspeaker is a boundary line. The broken line representations of the above-mentioned structures form no part of the claimed design. The region within the broken line boundary in FIG. 2 also forms no part of the claimed design.
